UNITED STATES PATENT OFFICE.

HERMAN SCHAEFER, OF ASTORIA, NEW YORK.

SUPPORT FOR SUSPENDED CONDUCTORS.

1,242,048.

Specification of Letters Patent.

Patented Oct. 2, 1917.

Application filed March 25, 1916. Serial No. 86,739.

To all whom it may concern:

Be it known that I, HERMAN SCHAEFER, a citizen of the United States, residing at Astoria, Long Island City, in the county of 5 Queens and State of New York, have invented certain new and useful Improvements in Supports for Suspended Conductors, of which the following is a specification, reference being had to the accompanying drawings.

This invention relates to means for supporting conductors, and particularly to means for supporting trolley wires or conductors of like character.

15 The general object of this invention is to provide a support for bare conductors including a straight line ear combined with a female bell-shaped cap or hanger.

A further object of the invention is to 20 provide a construction of this character wherein the ear is formed in two portions or sections, namely, an ear proper which extends beneath and supports the conductor for an appreciable distance and a trolley 25 wire clamping cap section which fits the upper face of the ear and is held down closely upon said upper face.

A further object of the invention is to 30 provide an ear so formed that the trolley wire or other conductor may be readily placed in engagement with the ear or removed therefrom, and provide means whereby the trolley wire may be clamped within a seat in the ear, said means being shiftable 35 out of its operative position to permit the detachment of the trolley wire.

A further object of this invention is to 40 provide an ear which may be connected to a bell hanger or without change connected 45 to a double or single suspension yoke or a feed yoke or a suspension bracket, and still another object is to provide an ear which may be used as a splicing ear or as means for connecting a feed wire to the trolley wire.

45 Other objects will appear in the course of the following description.

My invention is illustrated in the accompanying drawings, wherein:

Figure 1 is a transverse section of a conductor support constructed in accordance 50 with my invention;

Fig. 2 is a fragmentary side elevation of the support, the bell and cone not being shown, the view being partly in section;

55 Fig. 3 is a fragmentary elevation of the ear;

Fig. 4 is a fragmentary top plan view of the cap piece 26;

Fig. 5 is a side view of a portion of this cap piece;

Fig. 6 is a top plan view of the clamp 30;

Fig. 7 is an under side plan view thereof;

Fig. 8 is a perspective view of another form of hanger with my invention applied thereto;

Fig. 9 is a perspective view of another form of hanger with my invention applied thereto;

Fig. 10 is a side elevation of my improved ear partly in section; and

Fig. 11 is a longitudinal horizontal section through the members 23 and 26.

Referring to these drawings, 10 designates the bell which is made of metal or other suitable material and at its center is formed 75 with the socket 12 bounded by the outwardly extending annular flange 13 whose extremities are inwardly turned, as at 14. At the base of this flange the body of the bell is formed with an inwardly extending 80 flange 14. The extremities of the body 10 are provided with the hook-shaped span wire-engaging lugs 15. The span wire 16 is adapted to be disposed in these lugs, and extend around the bell-shaped skirt formed 85 by the flange 13.

Disposed within the socket 12 is the "cone" 17. While I term this part 17 a "cone", it is to be understood that it is not conical in form but substantially cylindrical with the outer face of the side wall concavely depressed as at 18. The interior of the cone 17 is bored and screw threaded for the reception of the shank 19. The socket 12 is intended to be filled with cement 90 95 whereby the member 17 will be held in place within the socket 12. The cone 17 may be of insulating material and the cement 12 will also act as insulation or may have partial insulating properties.

The "ear" as it is termed, which supports the trolley wire 21, comprises the shank 19 which is screw threaded and an elongated body 22 which extends at right angles to the axis of the shank and projects diametrically in opposite directions. The under face of this body 22 is curved longitudinally and the ends of the body slightly taper. Arching over the upper face of the body 22 at its middle is the hub 23 which extends transversely over the body and which is directly connected to the shank 19. It will be under-

stood, of course, that the portions 22 and 23 of the shank are preferably cast or otherwise formed in one piece. The upper face of the body 22 of the ear is transversely recessed, as at 24, so that the hub portion 23 arching over the grooved portion 22 provides an entrance passage 25 whereby the wire may be entered into the ear and seated in the groove 24. This is best illustrated 10 in Fig. 1. The end faces of the hub 23 are vertically grooved, as at 23^a, for a purpose which will be later stated. (See Fig. 2.)

Coacting with the ear section 22 and provided for the purpose of holding the trolley 15 wire or other conductor securely in place within the seat 24 is a cap section 26 which has a length equal to that of the portion 22 and a width somewhat greater than this portion and is tapered toward its ends and 20 has inclined end faces 27. Extending vertically through this cap section 26 at its middle is a passage 28 which is elliptical in form and is adapted to receive the hub portion 23 of the ear 22, as shown best in Fig. 25 4, this section 26 being cut away upon its under face, as at 29, to accommodate the outwardly flaring base of the portion 23, where it connects to the body 22, as illustrated in Fig. 5. The under face of the cap section 26 is 30 longitudinally grooved, as at 26^a, this groove corresponding with the groove 24 so that when the cap is in place the wall of the groove 26^a will extend over the groove 24. The shank 19 passes entirely through the 35 opening 28, and disposed to surround the shank and bear upon the upper face of the cap piece 26 is a clamping member 30 somewhat rectangular in plan with rounded corners and having a flat under face formed 40 with the longitudinally extending recesses 31. The center of the clamp 30 is formed with an opening 32 through which the shank loosely passes, and a nut 33 engages the shank and bears upon the top of the clamp. 45 This clamp, bearing as it does upon the cap 26, holds it securely down in place in engagement with the trolley wire. It will be seen that the grooves 31 communicate with the space around the portion 23 of the ear 50 22, as illustrated in Fig. 2.

The operation of the invention as a straight line ear is obvious from the drawing to all who are skilled in the art. By unscrewing the nut 33 and raising the clamping member 20 and the cap piece 26, it is an easy matter to detach the trolley wire from engagement with the ear and as easy to lock the trolley wire in place, the cap coming down when in place across the opening 55 25 and preventing any dislodgment of the trolley wire. Furthermore, the cap bears on its under face against the trolley wire and clamps it in firm position in the groove 24. It will be seen that it is not necessary to 60 65 detach the ear or hanger on the member 17

in order to attach or detach the trolley wire from the suspension device. It will further be seen that the ear 22 has contact over a relatively great length with the trolley wire so that there is no danger of strain on the 70 trolley wire breaking it either from the hanger or support or breaking it at the point of connection with the hanger or support. Furthermore, there is no necessity of soldering the trolley wire in place or bending over 75 lugs on the ears to temporarily engage the trolley wire before it is soldered to the ears.

As before stated, the ear constructed in accordance with my invention is not necessarily limited to use with the socket or bell disclosed in Fig. 1 and commonly used on trolley wire hangers, but it is equally adapted to be used in connection with double or single suspensions or with feed yokes. Thus 80 in Fig. 8 I show the improved ear as connected with a single yoke suspension, which single yoke is designated 35. This yoke has the ordinary form and is provided with an opening at the extremity through which the shank 19 passes, the clamping nut 33 85 being disposed upon the extremity of the shank so as to bear upon the upper part of the suspension hanger 35. This suspension hanger at its other end is bifurcated as usual and provided with the ordinary insulating turnbuckle 36 whereby it may be connected to span wires or guy wires.

In Fig. 9 I illustrate a double yoke suspension member, designated 37, having a medially disposed opening through which the shank 19 passes, the shank being held in place by the nut 33, as before stated. Both of these yokes are ordinary and well known and therefore require no further description. In Fig. 8 I show a modification of my ear 100 which may be used where it is desirable to connect span wires or guy wires to the ear, this construction being exactly the same as the construction previously described but the cap 26 being provided with ears 38.

The advantages of my invention are many. In all straight line suspensions or hangers known to me, the trolley wire is solidly or rigidly secured to the ear, as for instance, by inverting the ear and pouring 105 solder in around the wire or by hammering the sides of the ear inward around the trolley wire and bringing it almost to a knife edge. Now in case the trolley wire gets slack all 110 the ears on the slack section must be ripped off before the slack can be taken up, and that of course destroys the ears and they are good for nothing but the scrap heap. With my improved straight line ear it is only necessary to release the nut 33 which 115 will release the clamp 26, thus permitting the slack in the wire to be taken up, and after the slack in the wire has been taken up it is only necessary to again turn down the nut 33 to again urge the clamping member 120 125 130

26 into engagement with the wire. Furthermore, with the ordinary form of straight line ear the edges of the ear where they are forced around the trolley wire are very thin 5 and soon wear off, and when this occurs the ear is of no further use and therefore has to be thrown away and an entirely new ear put in. The ordinary ear can only be replaced at a cost of from 45¢ to 50¢, whereas 10 as if the ear 22 of my device wears out, which it will not do for a very long time, it will only cost 15¢. Furthermore, the trolley wire may be inserted or removed from the ear very readily by one man. It is only 15 necessary in applying the ear, to open the ear by turning up the jam nut 33, slipping the trolley wire in place through the opening 25, screwing down the jam nut 33, and, assuming that the bell-shaped cap has al- 20 ready been applied to the shank, springing the bell-shaped top on any cross span with the bell wrench in the usual manner. This takes less than five minutes to do, whereas other straight line ears must be screwed into 25 the bell hanger first, then the bell hanger sprung on a span wire, then two men lift the trolley wire into the straight line ear, and then the lateral edges of the straight line ear are pounded inward by a hammer 30 and anvil, taking at least ten minutes in order to do the job, whereas with my construction only five minutes are lost and only one man needs to be occupied with the work.

As before stated, this ear is adapted to 35 be used either as an ordinary line ear either connected directly to the span wire as heretofore described or connected to double or single suspension hangers, or it can be used as a splicing ear. This use of the device is 40 illustrated in Fig. 11. The parts of the mechanism illustrated are precisely the same as those illustrated in Figs. 1 to 7, the view, however, showing the adjacent ends of the trolley wire sections 21, these ends extending 45 upward through the grooves 23^a and the space 28 and being laterally bent and extending through the grooves 31 of the clamping member 30. Then when this clamping member is forced downward by 50 means of the nut 33 the two ends of the trolley wires are clamped in tight engagement with the hanger or ear and the two sections of the trolley wire are of course electrically connected to each other. It will be 55 seen that the grooves 31 are so formed as to make it impossible for the trolley wire to pull out unless the nut 33 is released. Feed wires may be connected to the trolley line wire in the same manner by bringing them 60 into one or the other of the grooves 31, extending them down through the space 28 and into engagement with the trolley wire 21.

A further advantage of my invention is 65 evident when it is desired to remove a

trolley wire from a portion of the system and replace it with a new trolley wire. In any one mile of trolley line there are about forty-five straight line ears. These ears are practically welded on the wire and when the 70 old wire is removed these ears are of no value. With my construction when it is desired to replace a line of wire it is only necessary to loosen the nuts 33 of the ears, remove the old wire, shove in the new wire, 75 and again clamp the wire in place. A straight line ear constructed in accordance with my invention of course does not have to be removed in order to replace or repair the line wire or take up slack. Attention is 80 also called to the fact that the opening 28 in the member 26 has its sides downwardly flared so that when the member 26 is in place upon the shank of the member 22 the side walls of the member 26 will extend down- 85 ward and outward over the member 22 along its entire length so that they form practically skirts which assist in shedding water and keeping water at this point from running down upon the trolley wire. In other 90 words, this performs to a certain extent the same function as performed by the skirt 13 or petticoats usually found on the bells of insulators or caps.

Having described the invention, what I 95 claim is:

1. A hanger for electric conductors comprising a metallic ear adapted to support a single conductor extending longitudinally the full length of the ear, and means for 100 detachably clamping the conductor in place in the ear, said means extending approximately the full length of the ear and said clamping means having an opening through its body whereby a second conductor may be 105 passed through the clamping means and clamped to the ear in electrical engagement with the first named conductor.

2. A hanger for electric conductors comprising an ear having a shank formed with 110 a conductor passage, the ear having a conductor seat on its upper face extending through the passage in the shank, and a clamping member loosely surrounding the shank and extending the length of the ear 115 and confronting said ear and adapted to clamp a conductor between the shank and the ear, the clamping member being spaced at one point from the shank to permit the introduction of a second conducting mem- 120 ber into engagement with the ear.

3. A hanger for electric conductors comprising a support, a shank extending at right angles thereto, a clamping member surrounding the shank and confronting the 125 support, a clamping member disposed upon the first-named clamping member and having a groove upon its under face extending to an opening in turn extending through the first named clamping member to the bot- 130

- tom thereof, and means for holding the clamping members in superposed relation to each other and urging said clamping members toward the supporting member.
5. A hanger for electric conductors comprising an ear having a screw threaded shank, the shank adjacent its junction with the ear being formed with a laterally opening conductor passage alining with the upper face of the ear, a bell including a screw threaded member to detachably receive the shank, a clamping member loosely surrounding the shank and vertically movable thereon and adapted to confront the ear and 10 when in operative position close the lateral opening in the shank, and a nut engaging the shank above said clamping member and adapted to hold the clamping member in operative position in relation to the shank, 15 there being a sufficient distance between the nut when in the last named position and the screw threaded member on the bell to permit the nut to be run up on the bell and permit the clamping member to be vertically 20 raised to a position to disclose the opening in the shank.
5. In a support for suspended electric conductors, the combination with a bell, of an ear having a shank detachably engaged with the bell, the ear extending longitudinally 25 and at right angles to the shank and having its upper face longitudinally grooved to form a seat for a trolley wire, the shank at its junction with the ear arching over the groove, a cap section longitudinally 30 grooved upon its under face and having a central opening adapted to engage over the shank and surround and arch over the shank to provide an entrance opening to the seat, 35 a rectangular cap member longitudinally grooved upon its under face and having a vertical opening through which the shank member passes, and a nut holding said cap in place.
45. 6. A hanger for electric conductors comprising an ear grooved upon its upper face and having a hub formed with a passage parallel to the face of the ear and with a slot intersecting said passage, a screw 50 threaded shank extending upward from the hub, a clamping member having an opening longer than the hub but having approximately the same width as the hub whereby to permit the introduction of conductors 55 between the end face of the hub and the adjacent face of the clamping member, and

means for holding the clamping member against the upper face of the ear.

7. A hanger for electric conductors comprising an ear having a shank, the upper 60 face of the ear for its entire length having a conductor receiving groove, a clamping member having an opening through which the shank passes and being shiftable toward and from the ear to clamp a conductor upon 65 the upper face of the ear, the opening in the clamping member through which the shank passes being larger in area than the area of the shank so as to permit the introduction of a conductor into the space between the 70 clamping member and the shank, and means for urging the clamping member toward the ear.

8. A hanger for electric conductors comprising an ear having a shank, the ear having a longitudinally extending groove upon its upper face adapted to receive a conductor, said groove extending the entire length of the ear, a clamping member having an 75 opening through which the shank passes and 80 whereby a second conductor may be electrically engaged with the ear and clamped, means for urging the clamping member toward the ear, and a second clamping member 85 operatively mounted upon the shank and holding the second named conductor in clamped engagement with the ear and the first named clamping member.

9. A hanger for electric conductors comprising an ear having a hub extending upward from its middle, the hub being approximately rectangular, a shank extending upward from the hub, a clamping member having an elongated opening through which the shank and hub pass, the opening 90 having a width approximately the same as the hub but being longer than the hub to permit auxiliary conductors to extend down between the hub and the clamping member, a second clamping member resting upon the 95 first member and adapted to engage said auxiliary conductors and clamp them in place, and means engaging the shank for forcing the clamping members downward 100 against the ear.

In testimony whereof I hereunto affix my signature in the presence of two witnesses.
